CINDER COLLECTOR

Roland L. Lincoln, Dedham, Mass., assignor to
B. F. Sturtevant Company, Boston, Mass.

Application May 13, 1941, Serial No. 393,174

2 Claims. (Cl. 183—80)

This invention relates to cinder and dust concentrators and collectors and relates more particularly to cinder concentrators for combination with induced draft fans.

In industrial plants such for example, as steam power plants utilizing induced draft fans, it is desired to separate cinders or other foreign particles from the gas before it enters the fans so as to avoid abrasion of the blades of the fan wheels.

This invention provides a compact, efficient cinder concentrator and collector which may be mounted in the inlet casing of an induced draft fan. Deflectors for causing abrupt changes in direction in the gas, may be mounted in the casing, around the axial inlet into the fan wheel. The gas entering through a tangential inlet, passes through the deflectors and the solid particles are thrown out by centrifugal force and are collected by a tangentially placed skimmer.

A feature of the invention resides in the provision of a partition which extends a substantial distance around and adjacent the deflectors for preventing the gas from flowing through the deflectors before it has acquired the desired spin which is imparted by the tangential inlet and the curved casing walls, and before it has acquired the desired velocity in its travel in the converging channel provided between the deflectors and the walls of the casing.

Another feature of the invention resides in the provision of spaced parallel partitions extending perpendicular to the axis of the collector and which serve to prevent the formation of the double eddy currents which tend to form in planes perpendicular to the direction of gas flow.

Another feature of the invention resides in providing a second skimmer at the end of said partition and extending across the gas stream between the deflectors and the partition.

Objects of the invention are to improve the efficiency and to reduce the size of and the cost of collectors for removing solid particles from gases.

The invention will now be described with reference to the drawing, of which:

Fig. 1 is a side sectional view of this invention embodied in the inlet of an induced draft fan, and

Fig. 2 is a side elevation with a portion of the casing removed, of a portion of the fan and collector of Fig. 1.

The fan illustrated has the volute inlet casing 5 with the tangential gas inlet 6. The casing 5 extends spirally around the axial inlet 7 into the

fan wheel 8. The gas moved by the fan wheel is discharged from the outlet 9. The construction described so far is old in the art and its details may be found in the U. S. Patent No. 1,846,863 which issued Feb. 23, 1932 on an application of H. F. Hagen.

The spaced deflectors 10 are arranged in a circular path in the inlet casing 5 and around the entrance to the inlet 7 into the fan wheel and serve to cause the gas flowing past them, to make abrupt changes in direction so as to throw out the entrained solid particles, by centrifugal force against the walls of the casing.

The tangential skimming channel 11 is formed in the walls of the inlet casing 5 at a point about 270° from the inlet 6. The deflectors 10 are so arranged in the casing 5 that the gas passage between the walls of the casing and the deflectors decreases progressively in diameter up to the skimming channel 11.

The partition 12 forms within the casing 5 an extension of the wall 13 of the casing, the two being formed in a circular segment which terminates in the pocket 14 formed between the lower end of the partition 12 and the wall 15 spaced inwardly therefrom. The partition 12 extends a substantial distance which as illustrated may be more than one-third of the way, from the inlet 6 into the casing 5; forms with the curved walls of the casing 5, a converging gas path, and serves to prevent the gas from passing directly between the upper deflectors 10, those adjacent the inlet 6, into the fan wheel. The gas cannot pass between the deflectors until it has passed the lower end of the partition 12, at which time it has developed sufficient spin and its velocity has increased so that the separation due to centrifugal force is considerably increased.

The pocket 14 has the lower wall 16 which as shown by Fig. 2 is inclined downwardly and terminates in the cinder outlet 17 which extends from the outer side wall of the casing 5. The pocket 14 thus extends into the gas passage between the partition 12 and the deflectors 10 and removes the solid particles thrown by centrifugal force against the partition 12.

The pocket 14 is not essential to the practice of the invention in so far as the above described functioning of the partition 12 is concerned and may be omitted without detracting from the value of the partition 12. With the pocket 14 omitted, the gas passing the lower end of the partition 12 will be recirculated, collection tak-

ing place in each circuit at the skimming channel 11.

The skimming channel 11 may be connected to the inlet of a cyclone type secondary collector which will remove the solid particles which are concentrated in the gas stream passing into the skimming channel 11.

Due to the motion of the gas around the inside of the spiral walls of the inlet casing 5, it tends to form the double eddy currents as illustrated by the arrows in the lower portion of Fig. 2. These eddy currents tend to take the solid particles concentrated by centrifugal force in the outer portions of the curved gas path, and to feed them back into the inner portions of the gas path thus decreasing the effectiveness of the desired concentration and separation. By providing the partitions 18 which extend in parallel planes perpendicular to the axis of the fan, from the point 19 in the inlet portion of the casing 5, to the skimming channel 11, the double eddy currents are prevented from forming. As illustrated by Figs. 1 and 2, the partitions 18 contact the outer wall of the inlet casing and extend inwardly a substantial distance towards the deflectors 10.

This invention may be used not only to collect cinders and fly ash from the flue gases of steam power plants, but may be used for collecting solid particles of any substance from any form of gas.

While one embodiment of the invention has been described for the purpose of illustration, it should be understood that the invention is not limited to the exact apparatus and arrangement and association of apparatus illustrated, as modifications thereof may be suggested by those skilled in the art without departure from the essence of the invention.

What is claimed is:

1. A dust collector comprising a casing having an outer curved wall, a tangential inlet passage for dust laden gas, an axial clean gas outlet, a

plurality of spaced deflectors arranged in a substantially circular path in said casing around said outlet for causing abrupt changes in the direction of the gas entering said outlet, means 5 forming a tangential skimming channel in said wall for collecting dust thrown thereagainst by centrifugal force, a partition extending at one end from said channel in a substantially circular arc in the direction of gas flow around not substantially less than half of said deflectors and extending into said passage towards said wall and substantially converging said passage, said partition forming between its outer side and said wall a converging passage for the gas in said casing and forming between its inner side and said deflectors, another gas passage for the gas passing said channel, and means at the other end of said partition forming another skimming channel for the dust thrown out by centrifugal force against said inner side of said partition.

2. A dust collector comprising a casing having an outer curved wall, a tangential inlet passage for dust laden gas, an axial clean gas outlet, a plurality of spaced deflectors arranged in a substantially circular path in said casing around said outlet for causing abrupt changes in the direction of the gas entering said outlet, means forming a tangential skimming channel in said wall for collecting dust thrown thereagainst by centrifugal force, a partition extending at one end from said channel in a substantially circular arc in the direction of gas flow around a plurality of said deflectors, said partition forming between its outer side and said wall a converging passage for the gas in said casing and forming between its inner side and said last mentioned plurality of said deflectors, another gas passage for the gas passing said channel, and means at the other end of said partition forming another skimming channel for the dust thrown out by centrifugal force against said inner side of said partition.
